CLAIM

The ornamental design for a fuse tube assembly for an electrical cutout, as shown and described.

DESCRIPTION

FIG. 1 is a perspective view of a fuse tube assembly for an electrical cutout showing our new design;
 FIG. 2 is another perspective view thereof;
 FIG. 3 is a right side elevational view, the left side being a mirror image thereof;
 FIG. 4 is a front elevational view thereof;
 FIG. 5 is a back elevational view thereof;
 FIG. 6 is a top plan view thereof; and,
 FIG. 7 is a bottom plan view thereof.

FIG. 1.

FIG. 2.

FIG. 3.FIG. 4.

FIG. 5.

FIG. 6.

FIG. 7.
